TO FAIRBANKS, MORSE & COMPANY, OF CHICAGO, ILLINOIS, A CORPORATION OF
ILLINOIS.

COMBINED GOVERNOR AND SPEED-REGULATOR.

1,201,821.

Specification of Letters Patent. Patented Oct. 17, 1916.

Application filed November 29, 1915. Serial No. 63,920.

To all whom it may concern:

Be it known that we, FRANKLIN G. HOBART and CHARLES B. JAHNKE, citizens of the United States, residing at Beloit, in the county of Rock and State of Wisconsin, have invented a certain new and useful Improvement in Combined Governors and Speed-Regulators, of which the following is a specification.

10 Our invention relates to combined governor and speed regulator for internal combustion engines.

The object of the invention is to provide means for holding an engine of this type 15 to a predetermined speed, in combination with means for predetermining or regulating the speed at which the engine is to run. Contributing to this general object it is our purpose to render the device self contained, 20 so that it may be preassembled and finally attached as a whole to the engine base.

We accomplish our object by the mechanism illustrated in the accompanying drawings, in which—

25 Figure 1 is an elevation of a portion of an internal combustion engine showing the same equipped with mechanism which embodies our invention. Fig. 2 is a plan view of the parts shown in Fig. 1. Fig. 3 is an 30 enlarged detail partly in horizontal section showing the chief operating parts of the governor and regulator. The line of section is indicated by the irregular line 3—3, Fig. 1. Fig. 4 is a detail looking in the direction of the arrow at 4, Fig. 1. Fig. 5 is an 35 elevation showing part of the head end of the cylinder. It also shows parts of the intake in section on the line 5—5, Fig. 1. Fig. 40 6 is an end view looking from the engine side showing the governor drag spring and associated parts.

Similar numerals refer to similar parts throughout the several views.

The engine 1, of which a portion only is 45 illustrated, is provided with the usual inlet passage 2. Controlling this passage is a valve 3 secured to a stem 4, as best shown in Fig. 5. This valve is normally held open by a torsion spring 5. Rigidly fastened to 50 the projecting stem 4 is an arm 6, which is connected by a rod 7 to the arm 8 of a bell

crank lever which is pivoted upon the pin 9 mounted in the governor bracket 10. This bracket is secured to the engine by bolts 11 or other suitable fastening means. The 55 other arm 12 of the bell crank is engaged by the projecting end of a spindle 13, which is mounted so as to freely slide longitudinally in the governor body 14. The bracket 10 is bored out so as to receive said governor 60 body and to permit the same to rotate freely. Said governor body is longitudinally chambered and contains a helical compression spring 15 which tends to move the spindle away from the arm 12. This spring at one 65 end abuts an annular shoulder 13^b on the spindle and at the other end abuts a threaded bushing 30 which screws into the outer end of the governor body. The bushing is notched at the outer end to take a 70 spanner wrench and affords a simple and convenient method of adjusting the tension of the spring, and permitting its removal.

The governor body is driven by a pinion 16 which meshes with a gear wheel 17 secured preferably to the cam shaft (not shown) of the engine. By preference, the gears are so proportioned that the governor body will rotate at somewhat higher than engine speed. The governor body has two 75 opposite and projecting arms 14^a which abut one side of the governor bracket, while the pinion 16 which screws onto the end of the governor body abuts the other end of the governor bracket, thus holding the governor 80 body in position while it rotates. At the ends of the arms 14^a are pins 20 which form pivots for the governor weights 21. These weights, with the governor body and associated parts, form what is frequently 85 termed a "fly ball governor." Extending from each weight is an arm 22, the end of which engages the end of a collar 13^a formed on the spindle 13. When the engine is at rest the compression spring 15 in the governor body acts upon the arms through the spindle and holds the weights in contact with the stops 14^b formed on the arms 14^a on the governor body. When the engine is 90 rotating, centrifugal force, urging the 100 weights outward, tends to move the arms 22 in a direction to compress the spring 15 and

move the spindle 13 in a direction to so operate the valve 3 as to reduce the speed of the engine.

The parts thus far described constitute a 5 governor and hold the engine to the speed for which it is regulated. We will now describe the speed regulator by which the engine may be set to run at greater or slower speeds.

- 10 The spring 25, which is constructed preferably of flat spring metal, bears against the end of a projection 13^a extending from the end of the spindle 13. The spring is rigidly secured to an arm 26 which is pivoted upon 15 the pin 27 carried by the governor bracket. An adjusting screw is mounted in said arm in such position that its inner end will abut the inner surface 10^a of the governor bracket. The arrangement is such that by 20 screwing the screw 28 down (toward the governor bracket) the spring 25 will be caused to exert greater pressure upon the spindle 13, thus supplementing the action of the centrifugal force generated by the 25 governor weights; hence, by screwing the adjusting screw down, the speed of the engine will be lowered, and by screwing it back, the speed will be increased.

We have provided means for preventing 30 the governor weights from acting too sensitively. The means for accomplishing this may be termed a "governor drag spring" and will now be described. The mechanism is best shown in Figs. 2 and 6 where it 35 will be seen that the hubs of the governor weights do not occupy the entire length of the pivot pins 20 between the arms 14^a but leave space for a spring 35, the ends of which are apertured to 40 receive said pins and bear against one end of each of the hubs. This is a flat steel spring and is engaged at the middle by an adjusting screw 36 screwing into the boss 37 formed upon one of the arms 14^a. The tension 45 of the spring may be regulated by screwing the screw in or out. It is held in its proper position by a lock nut 38. In operation, the spring presses against the hubs of the governor weights, thereby creating 50 friction and preventing the governor from responding too suddenly to variations in the engine's speed and making the engine more steady in its action.

As a result of our invention, it is possible 55 to set the engine for any desired speed and maintain the engine at that speed. Furthermore, this regulation in speed may be accomplished without shutting down the engine. The action will be smooth, for the 60 governor drag spring prevents the weights from acting too suddenly or in response to too small variations in speed. The parts are simple in form and comparatively few in number, and are durable and readily accessible. It will be noted also that the device

is self contained in the sense that the chief operating parts may be preassembled on a single supporting element (the bracket or frame 10) and the device as a whole subsequently bolted to the engine base.

Having thus described our invention, what we claim as new and desire to secure by Letters Patent, is:—

1. A centrifugal governor having two weights, a spring arranged to oppose the 75 centrifugal action of said weights, and a friction drag spring arranged to have frictional contact against both weights.

2. A centrifugal governor having a pivoted weight subject to the action of centrifugal force when the governor is in operation, a spring arranged to oppose the centrifugal action of said weight, and a friction drag spring arranged to press against said weight in the direction of the pivotal axis 85 thereof.

3. A centrifugal governor having a rotating governor body, pins carried by said governor body, governor weights pivotally supported upon said pins, and a drag spring pressing upon said weights in a direction parallel to the length of said pins.

4. A centrifugal governor having a rotating governor body, pins carried by said governor body, governor weights pivotally supported upon said pins, a drag spring pressing upon said weights in a direction parallel to the length of said pins, and an adjusting screw mounted in said governor body for regulating the pressure of said drag spring. 100

5. A self contained centrifugal governor for engines, said governor having a bracket constituting a frame on which the moving of the governor parts are supported, said moving parts including a plurality of weights, a 105 spring arranged to oppose the centrifugal action of said weights, and a friction drag spring arranged to have frictional contact against said weights.

6. A self contained centrifugal governor for engines, said governor having a bracket constituting a frame forming the sole support of the moving parts of the governor, and said moving parts comprising two weights, a rotating governor body journaled 115 in said bracket and pivotally supporting said weights, a spring in said governor body arranged to oppose the centrifugal action of said springs, means for regulating the tension of said spring, and a friction drag 120 spring arranged to have frictional contact against said weights.

7. A centrifugal governor having a plurality of weights, a spring to oppose said weights, a single drag spring adapted to 125 apply friction to said weights, all mounted on a common frame as a unit that may be separately assembled and attached to the motor.

8. A centrifugal governor having one or 130

more weights, a spring opposing the action of said weights, a drag spring to apply friction to said weights, a speed regulator having a spring adapted to augment or reduce the spring force opposed to said weights, all mounted on a common frame as a unit that may be separately assembled and attached to the motor.

In witness whereof we have hereunto subscribed our names.

FRANKLIN G. HOBART.
CHARLES B. JAHNKE.
